(57) **CLAIM**

The ornamental design for a microwave chip maker, as shown and described.

DESCRIPTION

FIG. 1 illustrates a top view of the claimed design for a microwave chip maker;
FIG. 2 illustrates a front view thereof;
FIG. 3 illustrates a right-side view thereof;
FIG. 4 illustrates a left-side view thereof;
FIG. 5 illustrates a rear view thereof;
FIG. 6 illustrates a bottom view thereof;
FIG. 7 illustrates a cross-sectional view thereof;
FIG. 8 illustrates a perspective view thereof; and,
FIG. 9 illustrates an exploded view thereof.
